UNITED STATES PATENT OFFICE.

WILLIAM C. BAKER, OF NEW YORK, N. Y.

IMPROVEMENT IN ELECTRICAL TEMPERATURE-REGULATORS.

Specification forming part of Letters Patent No. **152,031**, dated June 16, 1874; application filed March 27, 1874.

To all whom it may concern:

Be it known that I, WILLIAM C. BAKER, of the city and State of New York, have invented an Improvement in Temperature-Regulators for Buildings, &c., of which the following is a specification:

The object of this invention is to regulate the admission of atmosphere, in a heated condition or at ordinary temperature, into an apartment, according to the temperature of that apartment, so that when the temperature of the apartment is less than a fixed degree, warmed air will be admitted, but when it is higher than that degree the warmed air will be shut off, and cool atmosphere, at ordinary temperature, will be admitted into the flue and pass to the apartment in place of the heated air.

This improvement is especially adapted to use with steam heating coils or radiators; but there will not be danger from fire with furnaces, because the heat will be shut off at the furnace, and there will not be heat confined in the air-pipe, as usual when a register is closed at the room.

In the drawing, Figure 1 is an elevation of portions of a building with my improvements applied to regulating the introduction of atmosphere in connection with a steam-coil, and Fig. 2 is a plan of the circuit-closing thermostat.

The floors *a b* represent portions of any building in which this apparatus is applied. The case *d* is made to contain a steam or hot-water coil, radiator, or a heater of any desired character, and the air passes into this case through the trunk *e*, which preferably receives a supply of atmospheric air from outside the building. The trunk *f* or flue leads the heated atmosphere from the steam-coil to the room or apartment to be heated. The trunk or flue *g* unites with the flue *f*, and at the junction a damper, *h*, is placed that should be balanced so as to swing easily, and either close the warm-air flue *f* and open the cold-air flue *g*,

or vice versa. This damper *h* is actuated by a crank-arm and connection to the armature-lever *i* of the electro-magnet *k*. The thermostat *l* is, by preference, made of a coil composed of two flat strips, one of steel and the other of brass or similar metals, and the inner end of the coil is connected with the arbor of the hand *m*, and upon the dial are figures denoting degrees of temperature, so located that when the atmosphere of the apartment has attained the temperature designated the coil shall have expanded and its end moved sufficiently to close the circuit from the battery through the point *o*, and thereby energize the electro-magnets *k* and move the damper *h*, closing the warm-air flue and opening the cool-air flue *g*.

When the temperature has descended sufficient to cause the moving end of the thermostat to leave the circuit-point *o*, the circuit from the battery through the electro-magnet will be broken and the armature-lever *i* liberated, so that the damper returns to the normal position, and opens the warm-air flue and closes the cold-air flue.

I, however, do not confine myself to this particular construction of thermostat.

By this means the temperature of an apartment or building is regulated automatically, and, by the peculiar construction of the thermostat, the point at which the admission of hot air is shut off can be determined with great facility by simply moving the hand to the corresponding number on the dial.

I claim as my invention—

The combination of a thermostat circuit-closer and an electro-magnet with a damper and heated and cold air pipes, substantially as and for the purposes set forth.

Signed by me this 23d day of March, A. D. 1874.

W. C. BAKER.
